(57) **CLAIM**

The ornamental design for a handle for a lint roller, as shown and described.

DESCRIPTION

FIG. 1 is a perspective view of the new design for a handle for a lint roller;

FIG. 2 is a bottom view thereof;

FIG. 3 is a top view thereof;

FIG. 4 is a front view thereof, the rear view being a mirror image thereof;

FIG. 5 is a left side view thereof; and,

FIG. 6 is a right side view thereof.

Broken lines are used to show environment and boundaries that form no part of the claimed design.
